UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

FOREPART-TURNING MACHINE.

1,210,054.

Specification of Letters Patent. Patented Dec. 26, 1916.

Application filed January 27, 1916. Serial No. 74,574.

To all whom it may concern:

Be it known that I, ANDREW EPPLER, a citizen of the United States, residing at Lynn, in the county of Essex and State of Massachusetts, have invented certain new and useful Improvements in Forepart-Turning Machines; and I do hereby declare the following to be a full, clear, and exact description of the invention, such as will enable others skilled in the art to which it appertains to make and use the same.

The present invention relates to shoe turning machines and more particularly to machines for turning the forepart of a shoe.

Certain classes of turn shoes are provided with a stiffener member to form a box toe and considerable difficulty is experienced in turning these shoes owing to the tendency of the stiffener member to crumple or wrinkle during the turning operation, marring the appearance of the finished shoe.

The object of the present invention is to provide certain improvements in a forepart turning machine which enable shoes provided with box toes to be turned with facility and without wrinkling the stiffener member and displacing it relative to the upper. With this object in view a feature of the invention contemplates the provision in a machine provided with a shoe supporting form and a coöperating turning iron of a member which engages with the toe portion of the upper during the turning operation to retain the stiffening member in place and prevent the latter from wrinkling.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 represents a side elevation of a forepart turning machine embodying the features of the invention; Fig. 2 is a top plan view of the machine shown in Fig. 1; Fig. 3 is a detail illustrating upon an enlarged scale an elevation partly in section of the turning iron and coöperating upper engaging member in their retracted positions

prior to the turning operation; Fig. 4 is a view similar to Fig. 3 illustrating the turning iron and upper engaging member in their advanced positions prior to the turning operation; Fig. 5 is a detail illustrating the relative positions of the turning iron and upper engaging member during the turning operation; and Fig. 6 is a cross section upon the line 6—6 of Fig. 3 looking in the direction of the arrows.

The illustrated embodiment of the invention is preferably shown in connection with a machine of the type shown and described in the patent to Eppler, No. 706,038, August 5, 1902. This machine comprises the usual supporting base 1 having a vertically adjustable bracket 3 which carries a rotatable turret 4 having a series of radially projecting shoe forms 5. The supporting base 1 also carries a turning iron 7 which is mounted upon an arm 8 secured to a supporting shaft 9 rotated in bearings formed in a head 10 to move the turning iron into and out of operative relation to a coöperating shoe supporting form. The turning iron is retained in operative position by a pair of coöperating toothed collars 12 and 13 secured respectively to the shaft 9 and head 10 and normally retained in engagement by a spring 14. The toe of the shoe is clamped against the supporting form in the usual manner by the turning iron 7 and during the turning operation the sole of the shoe is supported by an auxiliary turning iron 15 pivotally supported upon a carrier 16 slidably mounted upon the turning iron 7 and arranged to be advanced into operative engagement with the shoe sole by a treadle 18 which is connected with the carrier through a bell crank 19 having its opposite arms connected respectively with the treadle through a link 20 and with the carrier through a link 21. The auxiliary turning iron is guided during the in and out movements by a face 25 formed on the turning iron 7 and engaged by the rear end of the auxiliary iron 15 which is pivoted upon the iron 7 at 24. The auxiliary turning iron is normally retained in a retracted position, as shown in Fig. 1, by a spring 26 connecting the treadle with the supporting base 1. In operating the

machine the shoe to be turned is first placed over a suitable skeleton supporting form 5 and the shaft 9 is then rotated to swing the turning iron 7 into the position 5 shown in Fig. 3 to clamp the toe of the shoe firmly against the form. The auxiliary turning iron 15 is then advanced into engagement with the under side of the sole at approximately the ball line to support 10 and form a preliminary break in the sole. The operator by then engaging the heel which has been previously turned is enabled to turn the forepart of the shoe from the ball toward the toe, gradually stripping the shoe 15 from the supporting form 5. During this turning operation the treadle is conveniently manipulated to permit a gradual retracting movement of the auxiliary turning iron toward the toe.

20 In the manufacture of turn shoes having box toes it is customary to thoroughly temper the stiffening member to put the member in a limp and pliable condition. In turning the shoe toward the toe, as ordinarily practised, there is great liability of the stiffener member crumpling and becoming displaced with relation to the upper. The stiffening and adhesive substance with which the member is coated, later hardens 25 and prevents the subsequent smoothing out of the member, causing the toe portion of the shoe to be permanently disfigured.

30 According to the present invention the toe portion of the upper containing the stiffening member is stretched firmly over the supporting form and held during the turning operation, effectually preventing any permanent wrinkling of the toe. This is conveniently accomplished by providing an upper 35 engaging member which engages with and stretches the upper over the support during the turning operation. As the turning operation progresses toward the toe the upper engaging member is yieldingly retracted, 40 the toe portion of the upper in the meantime turning about the tip of the upper engaging member which is in contact with the upper. In the simplest and most efficient 45 form of the invention which has yet been devised the upper engaging member is embodied in the type of machine above described and is yieldingly connected with the auxiliary turning iron. With this construction the upper engaging member is advanced with the auxiliary iron into contact 50 with the toe portion of the upper, after which the member is retained in yielding engagement with the upper during the continued advancing movement of the auxiliary 55 turning iron. In the machine shown in the drawings an upper engaging member is indicated at 30 and is secured at its rear end to a head 32 slidably supported upon the carrier 16. The head 32 is yieldingly connected with the carrier 16 by a tension 60

spring 33 and the normal position of the head with relation to the carrier is determined by the engagement of a shoulder 34 formed upon the carrier with the forward end of the head 32. In the normal position 70 of the head the upper engaging member 30 is positioned as shown in Fig. 3 with relation to the auxiliary turning iron. As the auxiliary turning iron is advanced prior to the turning of the shoe the upper engaging 75 member is also carried forward, wiping the toe portion of the upper over the supporting form 5. This advancing movement of the upper engaging member continues until a stop collar 35 engages with the face of a 80 bushing 37 threaded in the end of a recess 36 formed in the arm 8. The stop collar is formed upon one end of a rod 38 threadedly connected at its opposite end with the head 32 and provided with a lock nut 39 to lock 85 the rod in any adjusted position with relation to the head. With this construction the advanced position of the upper engaging member may be properly determined to retain the member in engagement with the toe portion of the upper and to permit a continued advancing movement of the auxiliary turning iron into the position shown approximately in Fig. 4.

90 In the preferred embodiment of the invention illustrated in the drawings the upper engaging member conveniently comprises an arm constructed and arranged to engage with the upper of the shoe at approximately the tip of the toe and ride up over 100 the toe, wiping the toe portion of the upper across the inclined face 40 of the supporting form. The arm is sufficiently flexible to permit a spreading movement of the upper engaging member with relation to the turning iron, effectually smoothing out the toe portion of the upper over the form. During the 105 turning operation proper, the auxiliary turning arm is retracted following the gradual turning of the shoe toward the toe, the upper engaging member meanwhile remaining substantially in the position shown in Fig. 4 through the action of the spring 33. When the auxiliary turning iron is retracted 110 to a position substantially opposite the upper engaging member the shoulder 34 contacts with the head 32, causing a rearward movement of the upper engaging member with the auxiliary turning iron to permit the turning of the toe portion of the upper. As the turning operation progresses toward the tip of the toe the upper engaging member is gradually retracted with the auxiliary turning iron retaining the upper 115 in position on the shoe supporting form.

120 While it is preferred to employ the specific construction and arrangement of parts shown and described, it will be understood that this construction and arrangement is 125 not essential except so far as specified in the 130

claims, and may be changed or modified without departing from the broader features of the invention.

The invention having been described,

5 what is claimed is;—

1. A shoe turning machine, having in combination, a shoe supporting form, a turning iron coöperating with the form and engaging with the toe portion of the shoe during 10 the turning operation, and a member engaging with the outside of the toe portion of the upper and arranged to maintain the upper stretched over the form during the turning operation.
- 15 2. A shoe turning machine, having in combination, a shoe supporting form, a turning iron coöperating with the form, an upper engaging member, and means for moving the upper engaging member into contact with the toe portion of the upper above the form.
- 20 3. A shoe turning machine, having in combination, a shoe supporting form, a turning iron coöperating with the form, an auxiliary turning iron, an upper engaging member connected with the auxiliary turning iron, and means for moving the auxiliary turning iron and upper engaging member into contact with the shoe on opposite sides of the form.
- 25 4. A shoe turning machine, having in combination, a shoe supporting form, a turning iron coöperating with the form, an auxiliary turning iron, an upper engaging member, yielding connections between the auxil-

iary turning iron and upper engaging member, and means for advancing the auxiliary turning iron and upper engaging member into contact with a shoe.

5. A shoe turning machine, having in combination, a shoe supporting form, a turning iron coöperating with the form, a carrier slidingly supported upon the iron, an auxiliary turning iron mounted upon the carrier, an upper engaging member supported upon the carrier, yielding connections between the carrier and upper engaging member, means for limiting the advancing movement of the upper engaging member, and means for advancing the carrier.

6. A shoe turning machine, having in combination, a shoe supporting form, a coöperating turning iron, an upper engaging member, and actuating means for causing the member to first engage with the tip of the toe and wipe the toe portion of the upper over 55 the shoe supporting form.

7. A shoe turning machine, having in combination, a shoe supporting form, a coöperating turning iron, an auxiliary turning iron, an upper engaging member, connections between the auxiliary turning iron and the upper engaging member, and means for advancing the auxiliary turning iron and upper engaging member into engagement with the shoe upon opposite sides of the shoe 65 supporting form.

ANDREW EPPLER.
